WELL CONTROL DEVICE

Chester A. Combs, Benavides, Tex., assignor of
 thirty-three and one-third per cent to B. L.
 Sherrod, Conroe, Tex.

Application January 14, 1941, Serial No. 374,383

9 Claims. (Cl. 103—232)

This invention relates to improvements in flow control and more particularly to a novel device for controlling the flow of fluids in oil wells, and it may be used either for wells that produce gas in insufficient quantity to force the oil to the surface or for wells artificially pressured.

After the initial flush production of an oil well, the reservoir of gas becomes depleted and usually salt water is present in considerable quantities. In a self-producing well, the oil at great depths is impregnated with gas in solution which, when rising, expands providing buoyance and lifting force to the oil.

If a well producing salt water is permitted to stand closed in for a period of time, the salt water rises to a considerable height above the bottom opening of the tubing, hence the water which rises part way when the choke or flow bean is opened, having little or no gas in the solution, fails to rise to the surface and is called "dead."

Now, if the well casing has considerable pressure either natural or induced, it is possible to start the flow again by utilizing perforations in the tubing spaced at various elevations to accord with the casing pressure, salt water percentage, etc. The perforations if left open after having accomplished their purpose are very wasteful of gas. The same is true if a means for closing said perforations fails to function either by staying open too long or by leakage.

The primary purpose of my invention is to supply simple practical means for effectively controlling such perforations and for tightly closing the perforations at the proper time.

A further object is to furnish a simple and inexpensive flow control device and yet one which will be exceedingly effective for the purpose for which it is designed.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a vertical sectional view partly in elevation of a portion of a well and showing one of my units with the parts in position to permit the flow of gas from the casing into the tubing containing the liquid.

Fig. 2 is a similar view of the flow control device with the view taken at right angles to the one in Fig. 1.

Fig. 3 is a horizontal sectional view on the line 3—3 in Fig. 1.

Fig. 4 is a vertical sectional view of a detail on the line 4—4 of Fig. 2.

Fig. 5 is a horizontal sectional view taken on the line 5—5 of Fig. 2.

Fig. 6 is a vertical sectional view of a detail taken on the line 6—6 of Fig. 1.

Fig. 7 is a vertical sectional view of well casing and an elevation of a tubing string with a number of my control units interposed therein.

Referring to the drawings, 8 designates well casing in which a tubing string 9 is arranged. In accordance with the invention certain sections 10 of the tubing are provided with one or more upper perforations 11 for the admission of gas, and one or more lower perforations 12 for the discharge of liquid. This section of the tubing is surrounded by a jacket 13 which is of slightly smaller diameter than the inside diameter of the casing and has its ends closed and secured to the tubing by joints 14. The jacket with the tubing forms an annular chamber 15 in which the liquid passing through the perforations 12 may rise and fall, so as to control an annular hollow float 16 filled with a non-volatile oil 17.

To take care of the severe pressures encountered in a well, the top and bottom of the float are connected to a vertically disposed hollow cell 18, which as best shown in Fig. 5, is provided with plane opposite side walls 19. Such walls can expand or contract and will therefore prevent breakage of the float due to the unequal pressures at the interior and exterior of the float.

For counter-balancing purposes, a pair of links 20 are pivotally connected to the bottom of the float and their lower ends are pivotally connected to rocking levers 21 that are pivotally connected at their medial portions (as indicated at 22) to a collar 23 fixed to the tubing. The levers pivotally support links 24 from which are suspended an annular weight 25.

Above the float, a block 26 is arranged in the chamber 15 and secured to the tubing. The block provides a passageway 27 placing the interior of the casing in communication with perforation 11. A valve seat 28 forming part of the passageway cooperates with a vertically reciprocating valve member 29 which is elevated by gas pressure within the casing. The valve is closed by means of a pin 30 which engages its head. The pin projects radially from a horizontally disposed rocking shaft 31 fixed to an arm or lever 32 that

is pivotally connected to the top of the float by a link 33.

As shown in Fig. 7, the units according to my device are arranged at various elevations spaced according to casing pressure, salt water percentage, etc. Each unit operates as follows. When the unit is above the liquid level in the tubing, the chamber 15 will be empty and the float will be in lowermost position and the valve 29 will be closed to prevent gas from the casing entering the tubing.

When the choke or flow bean on the well is open releasing the tubing pressure, the casing pressure forces the liquid down and up through the lower end of the tubing to a certain height. If this elevation is over the valve of one of my units, the liquid will enter the chamber 15 through the ports 12 and will compress the gas in the chamber above the liquid level. The liquid will cause the float to rise, hence link 33 will lift one end of the arm 32 to cause the finger 30 to move away from the valve 29. The pressure in the casing will open this valve and allow gas from the casing to enter the tubing. Hence the liquid in the tubing, above the valve will be forced upward and out of the well and the casing pressure will force liquid from a lower level into the tubing. When sufficient liquid has been removed or made lighter by gas bubbles in the tubing column, the valve below the last-mentioned valve being open, as is the first, will begin to function due to reduced pressure in the tubing and relatively constant casing pressure.

The gas released into the tubing by the lower valve will pass by the ports and part of this gas will enter these ports replacing the liquid, on the same principle as a stock or chicken fountain.

When the liquid is lowered sufficiently below the float, the latter moves downwardly and again closes the valve 29. It is to be noted that this operation takes place when a lower valve has begun to function, and that the time required for the upper valve to close is determined by the size and number of perforations leading from the tubing into the chamber 15. Since the jacket 13 is welded to the tubing, there is no chance for leakage except at the orifice leading to and through the valve.

While I have disclosed what I now consider to be a preferred embodiment of the invention, in such manner that the same may be readily understood by those skilled in the art, I am aware that changes may be made in the details disclosed without departing from the spirit of the invention as expressed in the claims.

What I claim and desire to secure by Letters Patent is:

1. In a flow control device for wells having a casing with tubing arranged therein, a jacket secured to a portion of the tubing and forming a gas-tight chamber, a port placing the interior of the tubing in communication with the lower portion of said chamber, a passageway placing the interior of the casing at the exterior of the jacket in communication with the interior of the tubing at a point above said port, a valve to control the passing of gas through the passageway, a float in said chamber, said chamber being segregated from the tubing above said float, whereby gas may be trapped in the chamber by liquid rising therein, and means operatively connecting the float to said valve to permit the valve to open when the float rises and to close the valve when the float descends.

2. In a flow control device for wells having a

casing with tubing arranged therein, a jacket secured to a portion of the tubing and forming a gas-tight chamber, a port placing the interior of the tubing in communication with said chamber, a passageway placing the interior of the casing at the exterior of the jacket in communication with the interior of the tubing, a valve to control the passing of gas through the passageway, a hollow float in the chamber filled with non-volatile oil, and means operatively connecting the float to said valve to permit the valve to open when the float rises and to close the valve when the float descends.

3. In a flow control device for wells having a casing with tubing arranged therein, a jacket secured to a portion of the tubing and forming a gas-tight chamber, a port placing the interior of the tubing in communication with said chamber, a passageway placing the interior of the casing at the exterior of the jacket in communication with the interior of the tubing, a valve to control the passing of gas through the passageway, a hollow float in said chamber filled with non-volatile oil, a pressure-equalizing passageway extending through the float and having expandible and contractable opposite walls, and means operatively connecting the float to said valve to permit the valve to open when the float rises and to close the valve when the float descends.

4. In a flow control device for wells having a casing with tubing arranged therein, a jacket secured to a portion of the tubing and forming a gas-tight chamber, a port placing the interior of the tubing in communication with said chamber, a passageway placing the interior of the casing at the exterior of the jacket in communication with the interior of the tubing, a valve to control the passing of gas through the passageway, a float in said chamber, counter-balancing means connected to the float, and means operatively connecting the float to said valve to permit the valve to open when the float rises and to close the valve when the float descends.

5. In a flow control device for wells having a casing with tubing arranged therein, a jacket surrounding a portion of the tubing and forming with the latter a gas-tight annular chamber, a port placing the interior of the tubing in communication with the lower portion of said chamber to permit liquid from the tubing to flow into the chamber, a passageway placing the interior of the casing in communication with the interior of the tubing, a valve to control the passing of gas through said passageway, an annular float arranged in the chamber, and operating means for the valve operatively connected to the float and valve.

6. In a flow control device for wells having a casing with tubing arranged therein, a jacket secured to a portion of the tubing and forming a gas-tight chamber, a port placing the interior of the tubing in communication with said chamber, a passageway placing the interior of the casing at the exterior of the jacket in communication with the interior of the tubing, a valve to control the passing of gas through the passageway, a float in said chamber, means operatively connecting the float to said valve to permit the valve to open when the float rises and to close the valve when the float descends, levers arranged in said chamber and having their medial portions pivotally connected to the tubing, means connecting the bottom of the float to certain ends of the levers, a counter-weight, and means

operatively connecting the other ends of the levers to said counter-weight.

7. In a flow control device for wells having a casing with tubing arranged therein, a jacket surrounding a portion of the tubing and forming with the latter a gas-tight annular chamber, a port placing the interior of the tubing in communication with the lower portion of said chamber, a passageway placing the interior of the casing in communication with the interior of the tubing, a valve to control the passage of gas through the passageway from the casing to the tubing, an annular float arranged in the chamber and guided by the tubing, diametrically opposite links pivotally connected to the bottom of the float, levers having their medial portions pivotally connected to the tubing and certain of their ends connected to the lower ends of the links, an annular counter-weight guided by the tubing, links extending upwardly from the counter-weight and connected to the other ends of said levers, and means operatively connecting the float to said valve to permit the valve to open when the float rises and to close the valve when the float descends.

8. In a flow control device for wells having a casing with tubing arranged therein, a jacket surrounding a portion of the tubing and forming with the latter a gas-tight annular chamber, a port placing the interior of the tubing in communication with the lower portion of said chamber, a block in the chamber between the tubing and jacket, a passageway extending through the block, a port in the tubing registering with said

passageway, a valve in the passageway to close communication between the interior of the casing and the interior of the tubing, a rock shaft pivotally mounted in the block and provided with means for closing the valve, an arm arranged in the chamber and having one of its ends rigidly united with the rock shaft, an annular float guided by the tubing and arranged in said chamber, and means connecting the float to the other end of said arm.

9. In a flow control device for wells having a casing with tubing arranged therein, a jacket surrounding a portion of the tubing and forming with the latter a gas-tight annular chamber, a port placing the interior of the tubing in communication with the lower portion of said chamber, a block in the chamber between the tubing and jacket, a passageway extending through the block, a port in the tubing registering with said passageway, a valve in the passageway to close communication between the interior of the casing and the interior of the tubing, a rock shaft pivotally mounted in the block and provided with means for closing the valve, an arm arranged in the chamber and having one of its ends rigidly united with the rock shaft, an annular float guided by the tubing and arranged in said chamber, means connecting the float to the other end of said arm, a counter-weight arranged in the chamber below the float, and link and lever means pivotally connected to the tubing and operatively connecting the counter-weight to the float.

CHESTER A. COMBS.
